CONTAINER

Mack R. Fields, Libertyville, Ill., assignor to Abbott Laboratories, North Chicago, Ill., a corporation of Illinois

Application March 9, 1949, Serial No. 80,539

9 Claims. (Cl. 128—272)

1

My invention relates to an improved medicinal container and more specifically to a container for use in a powdered medicament inhaling device, such as the device described in my copending application Serial No. 24,319, filed April 30, 1948 now Patent No. 2,470,296.

The device according to my invention is especially useful and convenient in the administration of a powdered medicament by inhalation of the patient and includes among its objects improved methods of manufacture of such containers.

Figure 1 is a perspective of a container according to the invention;

Figure 2 is a sectional view of the same container, and Figure 3 is an elevation of the foraminated end;

Figure 4 is a cross section of the closure shown in Figure 1;

Figure 5 is a cross section of a modification;

Figure 6 is a perspective of a holder for use with the container;

Figure 7 is a section indicating a modified closure and Figure 8 is a bottom elevation of the embodiment of Figure 7; and

Figure 9 is a cross section of a modified container and closure, and Figure 10 is an elevation of the embodiment of Figure 9.

In the embodiment of the device selected for illustration in Figures 1 to 4, the main housing 10 is a transparent molded plastic body. The body includes the tubular portion 11, closed by a concave upper end wall 12, and a foraminated lower end wall 13, to define the chamber for the powdered medicament.

The cup-shaped piece 14 has a slightly tapered exterior side wall 17, a straight interior side wall 36, and an outwardly bulged perforated end wall 18, having a convex radius of curvature of about 5 times the subtended arc. The cup 14 engages the body 10 in tight frictional engagement and is so constructed and assembled that there is a tight and smooth joint at the bottom 35 of the rabbet. The tight, smooth joint at 35 is necessary so that none of the powdered medicament will be lodged at the junction between the cup 14 and the body 10. The cup 14 is of a soft resilient plastic material.

Means are provided for assembling the container in a holder, such as the holder 60 of Figure 6. I have illustrated the barrel 10 with an outwardly projecting flange 19, having two engaging lugs 20, and a handle 21 for manipulation. The handle 21 has a knurled section 22 to facilitate handling.

2

The container is filled at the factory with the powdered medicament and the cup 14 is inserted into the rabbet 17 of the body 10, and pushed in tightly. The rubber closure 15 is fitted onto the barrel 10 with tight frictional engagement. In undistorted condition the bottom 25 of the closure 15 is bulged inwardly, so that when assembled it snugly engages the exterior surface of cup 14 as indicated in Figure 2.

The medicament container of the type contemplated is used in inhaling devices for administration of finely comminuted medicaments. Such a container readily adapts itself to piece-meal administration of the total dose of medicament contained therein. The container may be used in devices of various types, for example, inhaling devices where the container is agitated by a moving object to produce an impact to dispense a small amount of powder on each impact, devices where the container itself is moved and a small amount of powder is discharged by the impact of the container and a stationary stop, devices where the container is stationary and air is forced through the perforations to agitate and pick up a small amount of powder, devices where the entire device including the holder as well as the container is jolted at appropriate times to release small amounts of powder, and the like. In such a holder 60 as that of Figure 6 the container is stationary and a ball piston in the guide tube 61 shakes the container at the beginning of each inhalation.

In the embodiment of Figure 5 the molded cup 30 has an integral foraminated end 31 having holes 50. The closure 15 engages the barrel 30 in a tight engagement covering the holes 50, and the powdered medicament is filled into chamber 51. The top 32 carrying the manipulating handle 21 is then fitted onto the cup 30 in permanent assembly as by a frictional fit, threaded engagement, glued engagement, etc.

In the embodiment of Figure 9 the cup-shaped end piece 53 is similar to cup 14 except for having a rim 41 to receive the closure 52. The closure 52 is retained by edge engagement with the rim 41 and carries an integral retroverted tab 54, by means of which it can readily be disengaged and removed.

In Figures 7 and 8 the cover 33 is applied to the cup 14. It has a tab 40 to facilitate removal, and may be held in place by adhesive.

In Figures 7 and 9 a protective closure such as a thin metal foil 33 and 52 respectively, or a like material, engages the perforated end of the container. In Figure 7 the closure 33 is glued on and

3

in Figure 9 the closure 52 frictionally engages a slight rim 41 on cup 53. The closure 33 may be removed by means of the tab 40, which will cleave away from the cup 14 when pulled. Likewise the closure 52 is removed from engagement with rim 41, by means of a pull on tab 54.

The dimensions of the holes in the perforated end wall of the container may be designed to secure effective retention of various kinds of powder, except when jolted, taking into consideration the grain size and flow characteristics of the particular powder involved. Then the number of holes can be made such as to secure the desired amount of discharge with one jolting. It is possible to secure the desired characteristics in both respects, and still have the end wall sufficiently open to permit the powder to be blown out through one portion of the end wall 18 by blowing an air current in through another portion of the same end wall 18. As an illustration, I have discovered that with powdered penicillin seven tapered holes are very satisfactory for dispensing such powder. The desired taper on the holes is obtained by having the exterior diameter of the hole 0.052 inch and the interior diameter of the hole 0.045 inch, when the end wall 18 is about 0.015 inch thick. The end wall and holes of these dimensions have proved satisfactory with a container of about 0.25 inch internal diameter and about 0.5 inch long.

Others may readily adapt the invention for use under various conditions of service, by employing one or more of the novel features disclosed or equivalents thereof. All the materials specifically disclosed hereinabove may be replaced to suit various service conditions. It is desirable, however, to have a transparent container so that it is possible to ascertain the amount of powder remaining in the container. As at present advised with respect to the scope of my invention I desire to claim the following subject matter.

I claim:

1. A dispensing container for powdered medicament comprising, in combination: two elements telescopically assembled to define a chamber; one of said elements being a tubular member having a concave end wall at one end and a tapered rabbet comprising a substantial portion of the internal tubular wall at the other end thereof; the other said element being an internally fitting cup having an exterior tapered wall, a straight interior wall, and a perforated end wall having a plurality of outwardly tapered perforations.

2. A dispensing container for powdered medicament comprising, in combination: two elements telescopically assembled to define a chamber; and a closure for sealing said chamber; one of said elements being a tubular member having a concave imperforate end wall at one end, a tapered rabbet comprising a substantial portion of the internal tubular wall at the other end of said tubular member, and external means for engaging a receiving holder; the other said element fitting in said rabbet, having an exterior tapered side wall, a straight interior side wall, and a perforated end wall having a plurality of outwardly tapered perforations; said closure being cup shaped, and having an end wall engaging said perforated end wall, and a side wall fitting over the external side walls of said tubular member.

3. A dispensing container for powdered medicament comprising, in combination: two elements telescopically assembled to define a chamber; and a closure for sealing said chamber; one of said elements being a tubular member having a con-

4

cave imperforate end wall at one end, a tapered rabbet comprising a substantial portion of the internal tubular wall at the other end of said tubular member, and external means for engaging a receiving holder; the other said element telescopically engaging said rabbet, having an exterior tapered side wall, a straight interior side wall, a perforated end wall having a plurality of outwardly tapered perforations; said perforated end wall having an exterior axially projecting flange; said closure being an imperforate disc engaging interiorly the said axial flange; and means for disengaging said disc from said axial flange.

15 4. A dispensing container for powdered medicament comprising in combination: a sealed chamber having a perforate end wall containing a central circular opening and six additional openings of the same diameter, uniformly spaced around the central openings; said end wall being outwardly convex with a radius of curvature about five times the subtended arc; each hole being tapered with its large end outermost; each hole having its minimum inner diameter about three times the wall thickness and its maximum outer diameter about three and one half times the wall thickness.

20 5. A dispensing container for powdered medicament comprising, in combination: a tubular body; an imperforate concave end wall at one end of said body and an internal tapered rabbet at the opposite end thereof; an internal cup-shaped closure seated in said rabbet closing the open end of said body; said closure having a plurality of outwardly tapered spaced openings adapted to dispense powdered content; an axially aligned handle extending beyond said imperforate end wall; a radial flange encircling said body adjacent said handle; positioning lugs oppositely radiating on said flange; and a removable seal closing said perforations.

25 6. A dispensing container for powdered medicament comprising, in combination: two elements telescopically assembled to define a chamber; one of said elements being a tubular member having a concave end wall at one end and an inwardly-facing tapered rabbet at the other end thereof; the other said element being an internally fitting cup having an exterior tapered wall of a dimension to be forced into said rabbet tightly enough to secure a substantially permanent assembly, a straight interior wall, and a perforate end wall.

30 7. A dispensing container for powdered medicament comprising, in combination: two elements telescopically assembled to define a chamber; one of said elements having an imperforate closed end portion and a tubular portion extending away from said closed end portion; the edge 35 of said tubular portion having an inwardly facing tapered rabbet; the other said element being an internally fitting cup having an exterior tapered wall of a dimension to be forced into said rabbet tightly enough to secure a substantially permanent assembly; said cup having a perforated bottom at the large end of said tapered wall; the small end of said tapered wall presenting an annular surface lying in a transverse plane to abut the small end of said tapered rabbet; said 40 tapered wall and tubular portion having the same internal diameter in the plane of abutment, whereby the assembled parts present a smooth confining surface to the contents of said container.

35 8. A dispensing container for powdered me-

dicament comprising, in combination: two elements telescopically assembled to define a chamber; one of said elements having an imperforate closed end portion and a tubular portion extending away from said closed end portion; the edge of said tubular portion having an inwardly facing tapered rabbet; the other said element being an internally fitting cup having an exterior tapered wall of a dimension to be forced into said rabbet tightly enough to secure a substantially permanent assembly; said cup having a perforated bottom at the large end of said tapered wall; the small end of said tapered wall presenting an annular surface lying in a transverse plane to abut the small end of said tapered rabbet.

9. A dispensing container for powdered medicament comprising, in combination: two elements telescopically assembled to define a chamber; one of said elements having an imperforate closed end portion and a tubular portion extending away from said closed end portion; the edge of said tubular portion having an inwardly facing tapered rabbet; the other said element being an internally fitting cup having an ex- 25

terior tapered wall of a dimension to be forced into said rabbet tightly enough to secure a substantially permanent assembly; said cup having a perforated bottom at the large end of said tapered wall; the small end of said tapered wall presenting an annular surface lying in a transverse plane to abut the small end of said tapered rabbet; said cup, when assembled, being completely housed in said rabbet except for its transverse bottom surface, whereby removal of said cup is substantially prevented.
